UNITED STATES PATENT OFFICE.

ENOCH K. THOMAS, OF NEW YORK, N. Y., ASSIGNOR OF ONE-HALF TO
HENRY SCHIFFER, OF SAME PLACE.

DESIGN FOR CURTAIN-CLOTH FOR AWNINGS.

SPECIFICATION forming part of Design No. 28,305, dated February 15, 1898.

Application filed August 18, 1897. Serial No. 648,727. Term of patent 7 years.

To all whom it may concern:

Be it known that I, ENOCH K. THOMAS, a citizen of the United States, residing in the city, county, and State of New York, have invented a new Design for Curtain-Cloth for Awnings, of which the following is a specification.

This invention relates to a design for curtain-cloth for awnings; and I do hereby declare that the accompanying drawing, taken in connection with this specification, conveys to any one a clear understanding of the invention sufficient to enable such person to understand and use the same.

The invention resides in the unitary article shown in the drawing, wherein *a* are short

discontinuous stripes running lengthwise of the web and of contrasting colors, and *b* are broad continuous cross-stripes. The stripes *a* begin and end with the opposite lateral edges of the stripes *b*.

What I claim as new, and desire to secure by Letters Patent, is—

The design for curtain-cloth for awnings, substantially as shown and described.

In testimony whereof I have signed my name to this specification in the presence of two subscribing witnesses.

ENOCH K. THOMAS.

Witnesses:

NICHOLAS M. GOODLETT, Jr.,
SIDNEY MANN.
